United States Patent Office.

J. G. EVENDEN, OF CHICAGO, ILLINOIS.

Design No. 5,022, dated June 20, 1871.

DESIGN FOR A WOOD-INCASED CAN.

The Schedule referred to in these Letters Patent and making part of the same.

To all whom it may concern:

Be it known that I, J. G. EVENDEN, of Chicago, in the county of Cook and State of Illinois, have invented and produced a new and original Design for Wood-Incased Cans, of which the following is a specification.

The nature of my design is fully represented in the accompanying drawing, to which reference is made.

The body A of the can is square, and is incased in wood, w.

The breast or top B is pyramidal, terminating at its upper end in a small tubular nozzle, n.

A bail, C, is provided, and an air-vent, v, applied to the breast, as shown.

A lifting-ring or handle, m, is attached to the outside of the case.

Having thus described my invention, What I claim as new, and desire to secure by Letters Patent, is—

The design for a wood-incased can, herein shown.
J. G. EVENDEN.
